United States Patent Office

Des. 188,316
Patented July 5, 1960

188,316

SUPPORT FOR A REAR VIEW MIRROR

Anthony M. Lombari, 8709 1/4 S. Hoover, and Edwin L. Schwartz, 2429 Guthrie Drive, both of Los Angeles, Calif.

Filed June 8, 1959, Ser. No. 56,250

Term of patent 14 years

(Cl. D14—6)

Fig. 1.

Fig. 2.

Fig. 3.

Fig. 4.

Fig. 1 is a side elevational view of a support for a rear view mirror, showing our new design;

Fig. 2 is a front elevational view;

Fig. 3 is a top or plan view; and

Fig. 4 is a rear elevational view thereof.

The essential features of my design reside in the portions shown in full lines.

We claim:

The ornamental design for a support for a rear view mirror, as shown and described.
